SELF-PRIMING PUMP

Richard D. Campbell, Wauwatosa, Wis., assignor to Allis-Chalmers Manufacturing Company, Milwaukee, Wis., a corporation of Delaware

Application May 14, 1943, Serial No. 486,939

15 Claims. (Cl. 103—113)

This invention relates to improvements in self-priming pumps and particularly to self-priming centrifugal pumps in which recirculation of the water for priming is automatically cut off when the discharge conditions of the pump change as a result of completion of the priming action.

Centrifugal pumps are impulsive displacement machines and cannot discharge liquids until all of the gases have been removed from the suction line and the pump casing. Such gas removal or priming may be accomplished by completely filling the suction line and the pump casing from a source of liquid at a higher elevation, by removing the gases by the use of a separate evacuating pump or by causing entrainment of the gases by liquid recirculating within the pump and then releasing the entrained gases to the discharge line thus making the pump self-priming. Self-priming pumps, after completion of the self-priming action, should of course be as effective as other centrifugal pumps both as to the depth from which liquids can be lifted and as to the efficiency with which liquids are discharged. It is desirable that such self-priming pumps be operative at all times after the initial starting action regardless of how frequently the reservoir from which the liquid is obtained, is completely emptied. The priming action should be as rapid and smooth as possible to avoid the occurrence of power losses and the production of intermittent stresses in the pump structure.

The recirculating control valve should be unaffected by variations in the suction lift during the priming action and is preferably operative only in response to the discharge velocity of the pumped liquid. The valve should close as soon as the need for recirculation of liquid has ceased and the valve should be so designed as to be insensitive to operating conditions and not subject to misadjustments during use.

It is therefore an object of the present invention to provide an improved self-priming centrifugal pump in which water is recirculated only so long as priming is required as is determined by the discharge from the pump impeller itself.

Another object of the invention is to provide an improved self-priming centrifugal pump in which a valve is placed on the discharge side of the pump to control the recirculation of liquid for entrainment of such gases as may be present in the suction line of the pump.

Another object of the invention is to provide an improved self-priming centrifugal pump in which the recirculating valve is responsive only to the velocity of water discharged and is not

affected by the varying suction lift or discharge head of the pump during the priming action.

Another object of the invention is to provide an improved self-priming centrifugal pump in which the water flowing through the recirculating valve is continuously and immediately picked up by the pump impeller, thus preventing an intermittent priming action producing intermittent stresses in the pump structure.

Objects and advantages other than those above set forth will be apparent from the following description when read in connection with the accompanying drawing in which:

Fig. 1 is a vertical sectional view taken on the line I—I of Fig. 2 through the axis of both the valve chamber and the pump to show the valve structure and the relation of the valve controlled flow to the flow passing through the pump;

Fig. 2 is a top plan view of the entire self-priming pump structure;

Fig. 3 is an elevation taken from the inlet or suction side of the pump with a portion of the valve chamber wall broken away and with the recirculation control valve shown in vertical section on a plane taken centrally therethrough to illustrate the relation of the valve with the other portions of the structure; and

Fig. 4 is a horizontal section taken on the plane of the line IV—IV of Fig. 1 to show the relation of the port controlled by the recirculating valve with the inlet of the pump as well as to show the shape and location of the discharge passage from the pump and leading through the valve.

It will be understood, of course, that the pump may also be placed with the shaft in vertical position or at any other angle to the horizontal.

Referring more particularly to the drawing by characters of reference, the reference numeral 6 designates a casing enclosing an open type impeller 7 and forming a pump of the centrifugal type, it being understood that any known type of impeller may be used. The pump impeller is mounted on a shaft 8 to which power is to be applied by any known driving means (not shown) and the joint between the stationary casing and the rotating hub of the impeller is closed by a packing gland 9. The inlet through the pump casing 6 into the eye of the impeller is designated at 11 and the discharge passage from the usual volute portion of the casing 6 is shown at 12.

A chamber generally designated at 13 is mounted adjacent or, preferably, formed integral with, a portion of the pump casing 6 in such manner as to form one side thereof with the pump inlet 11 formed in the wall portion between the pump

casing itself and the chamber 13, as shown. The casing outlet and discharge conduit 12 extend outwardly from the volute portion of the casing and upwardly to open into the chamber 13 at one side thereof. Water is admitted to the intake portion of the chamber 13 by way of a suction pipe 14 provided with a check valve 15 and the water thus admitted flows through an inlet conduit portion defined by walls 16 formed on the inner wall of the chamber and through the inlet 11 into the impeller 7, and water is discharged from the pump through the discharge outlet 12 and the other side of the chamber 13 into a discharge pipe 17. The chamber 13 is provided with a cover 18 having a removable plug 19 by way of which the chamber may be initially filled with water, it being understood that such filling is required only the first time the pump is started. It will be seen that the inlet conduit formed by walls 16 provides a complete and separate passageway on one side of chamber 13 from the inlet pipe 14 to the pump casing inlet 11 and is wholly separated from the discharge space within the chamber except for controlled ports to be described.

The pump outlet 12 opens into a pocket formed in the bottom of the discharge space of the chamber 13 to provide a receptacle for a valve housing having a cylindrical body portion 20 with internal flanges 21 and 22 and an external flange 23. A spider comprising a central ring 26 and four arms 27 is mounted on flange 22 of the valve housing and a centrally apertured screen 28 is mounted on the flange 23 and extends over the spider. The valve housing encloses and guides a movable valve body formed with a hollow cylindrical bottom portion 31 having an external flange 32 and with an internal flange 33 from which extends, at right angles thereto, a smaller hollow cylindrical upper valve portion 34 extending above the valve housing into the chamber 13. The lower valve flange 32 fits into the valve housing and the lower cylindrical valve portion 31 fits into the opening formed by the valve housing flange 21 for the purpose of aiding in guiding the valve in its vertical movement. The upper valve extension or nozzle 34 also fits closely in the ring 26 of the spider to guide the vertical movement of the upper valve extension 34. The fit of housing flange 21 and lower cylindrical valve portion 31 in the valve housing also increases resistance to leakage about the periphery of such flange thereby preventing air flow back to the suction space with consequent increase in priming time required and loss of priming efficiency due to only partially effective discharge.

The spaces about the spider arms 27 provide passages through which water may flow from the chamber 13 between the flange 22 of the valve housing and the valve body extension 34 and through a port 36 in the valve housing located between flanges 21 and 22 and adjacent the impeller inlet 11. The valve housing is joined to a helical spring 37 under tension and having one end thereof fastened to a plate 38 on which the valve housing is seated and retained in the pocket provided therefor. The vertical movements of the valve are also, at least in part, guided by the spring 37. Due to guiding of the valve by the various flanges, the spider and the spring, it is impossible for the valve body to move from a vertical position sufficiently to cause jamming of the valve under any circumstances.

One wall 16 defining the suction conduit within the chamber 13 is provided with an aperture 41

connecting the suction space 42 of the chamber 13 with the discharge space 43 thereof and the aperture may be closed by a ball check valve 44. If the check valve 44 should not seat tightly and allow water to syphon back into the suction pipe 14 when the pump is not running, the ball check valve 44 will open and break the syphon action thus preventing drainage of all water from the chamber 13.

When the pump is at standstill, the flap check valve 15 is closed and the recirculating control valve 31 to 34, inclusive, is drawn downwardly by the spring 37 into the position shown in Figs. 1 and 3 of the drawing. If the pump is to be started, the space 43 of the chamber 13 must first be filled with water through the opening which is closed by the plug 19. The pump can then be started and water from the space 43 is drawn through a priming or recirculating path designated *a*, between the valve housing internal flange 22 and the valve cylindrical upper portion 34 to flow through the port 36 into the inlet 11 of the impeller 7. Water is discharged from the impeller through the outlet 12 and passes up through the valve 31-34 into the space 43 of the chamber 13 in which air separates from the water and passes out through the discharge pipe 17. Separation of gas from liquid in space 43 is promoted by valve extension 34 which acts as a nozzle to discharge the gas liquid mixture with sufficient force to carry the gas bubbles beyond recirculation path *a*. Entrainment of the gas bubbles is minimized by the screen plate 28 mounted on the valve housing and fitting relatively closely about the valve extension 34 thus blocking return of gas bubbles of any size through the recirculation path. The above recirculation of water through the path *a* continues until all of the air is drawn out of the suction conduit space 42 and the suction pipe 14 whereupon all of such parts are filled with water and the pump discharges its full capacity of water. It has been found that the pump structure herein disclosed will prime with a suction lift up to 27 feet in one and one-half minutes at a speed of 2250 R. P. M. and that the pump will prime in slightly less than three minutes at a speed of 1750 R. P. M.

During recirculation of a gas and water mixture in the path *a* the spring 37 holds the valve 31-34 substantially in the position shown with the recirculation or priming ports at least partially open. However, as soon as the pump is discharging only gas free liquid, the velocity of the discharge acts on the inner surface of the valve flange 33 and raises the valve 31-34 against the tension of the spring 37 until the flanges 22 and 33 of the valve body are seated on the flanges 21 and 22 of the valve housing thereby closing off the recirculation path *a*. Expressed in different language, lifting of the valve results from the differential pressure due to high suction lift and zero or low discharge or positive static head thus producing an increase in velocity through the valve. As the valve lifts the velocity decreases to a constant rate and hence the valve can operate under varying suction and discharge heads. Upon closure of valve 31-34, water flows through the normal pumping path *b*, that is through the suction pipe 14, the suction conduit space 42, the impeller inlet 11 and is forced by the impeller 7 into the volute portion of the casing 6 from which the water flows through the casing outlet 12, the valve 31-34, the discharge space 43 of the chamber 13, and is discharged through the discharge pipe 17.

The present structure has been found to have a number of critical characteristics. Thus the recirculation port 36 must be located adjacent to and in line with the impeller inlet 11 to allow the impeller 7 to pick up water immediately and continuously. Location of the port 36 as shown allows the jet of water issuing therefrom to entrain air in the suction space 42 continuously and to carry it immediately into the impeller. There is no release of such entrained air and there is no loss of time or power due to unnecessary turbulence in the suction space 42. If the recirculation port is located in any other position, the suction space 42 must be filled up to the level at which more than one-half of the pump inlet 11 is under water before the impeller will pick up the water. The impeller then picks up charges of water interspersed with a quantity of air and delivers the charges of water as solid masses to the recirculation path *a*. Such so-called "slugging" imposes intermittent stresses on the entire pump structure and its operating means and momentarily causes the valve 31-34 to lift. As soon as each slug passes into the discharge space 43, the stresses on the pump are relieved and the valve 31-34 is retracted by the spring 37 thus causing hammering of the valve. Under such conditions the pump cannot prime smoothly and continuously and the time required for priming is greatly increased. Location of the port 36 as shown has the further advantage that water is delivered directly into the impeller so there is no tendency for even the highest suction lift to so affect the valve as to vary the action of the discharge velocity thereon. Increase in suction lift therefore has no effect on the valve movement.

The vacuum drawn by the pump in the suction space 42 varies from 0 to 27 feet of water and if not equalized, would act directly on the valve 31-34. Such action would vary as the suction lift varies and would vary the action of the valve. But if the cross-sectional area of the port 36 and the other controlled portions of the recirculation path *a* are made smaller than the cross-sectional area of the valve chamber as defined by flanges 21, 22 and body 20 of the valve housing, a pressure is built up in the valve chamber and neutralizes the effect of the variable suction lift on the valve. The valve 31-34 is therefore actuated only responsive to the velocity of flow through the valve and a single spring 37 satisfactorily controls valve movement over the entire range of the suction lift. Further, the smaller port area increases the gas liquid mixture velocity beyond the point at which the gas may separate and also limits the flow to the impeller to prevent flooding thereof.

The stroke of the valve 31-34 between closed and wide open position, that is the space between the flanges of the valve housing and the valve, should be kept to relatively close limits. If the valve travels less than $\frac{3}{8}$ inch the spring tension must be increased beyond the ten pounds found satisfactory in practice and the valve then slams open and shut. And an increase in the valve stroke beyond $\frac{3}{4}$ inch makes it necessary to increase flange area 33 to such an extent that much turbulence is caused and efficiency is lost in flow through the valve. Such stroke limitation also prevents the valve from moving other than in a vertical direction and becoming jammed.

The nozzle portion 34 of the recirculating valve must extend above the bottom of the discharge space 43 for a sufficient distance to allow complete separation of the air from the recirculating

water outside of the recirculation path *a* and thus permit escape of such entrained air up through the discharge pipe 17. If the valve is made too short the entrained air is recirculated with the water and no priming action takes place.

A ratio, dependent on the tension of the spring 37, must be maintained between the area of the inner surface of the flange 33 of the recirculation control valve, on which the velocity pressure of the water acts to shut off the valve, and the area of the portion 34 of the valve through which the pump discharge must flow. The ratio, having a given spring tension, must be such that the valve is closed as soon as the volume of water pumped is greater than the volume of the water which can return through the recirculation port 36.

And the discharge head is related to the area of the bypass port 36. For higher discharge heads, the port must be made smaller because a greater quantity of water flows through the recirculation path, increasing the velocity of the air-water mixture beyond the point at which the air is readily released. The velocity must be kept down either by decreasing the port area or increasing the volume of space 43.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

35. 1. In a self-priming centrifugal pump, a casing, an impeller rotatable within said casing, a chamber mounted on said casing and divided into a suction space connected with the inlet of said impeller and separated from a discharge space receiving the discharge from said casing, a hollow valve member defining a passage through which the entire discharge from said casing is conducted to the discharge space of said chamber under all conditions of pump operation, said 40 valve member being slidably mounted to control a port connecting the suction and discharge spaces in said chamber, and spring means cooperating with said valve member to maintain communication between said suction and discharge spaces through said port when said pump is inoperative and during priming thereof.

2. In a self-priming centrifugal pump, a casing, an impeller rotatable within said casing, a chamber mounted on said casing and divided into a suction space connected with the inlet of said impeller and separated from a discharge space receiving the discharge from said casing, a ball 55 check valve controlling an aperture in the wall separating the suction and discharge spaces in said chamber to break any siphon action in the suction space, and a valve member conducting the entire discharge from said casing into the discharge space of said chamber and controlling a port connecting the suction and discharge 60 spaces in said chamber.

3. In a self-priming centrifugal pump, a casing, an impeller rotatable within said casing, a chamber mounted on said casing and divided into a suction space connected with the inlet of said impeller and separated from a discharge space receiving the discharge from said casing, a valve 70 housing mounted in the discharge space of said chamber and having a port connecting the suction and discharge spaces in said chamber, and a hollow valve element mounted for sliding move-

ment in said valve housing for conducting therethrough the entire discharge from said casing into the discharge space of said chamber under all conditions of pump operation and controlling said port for recirculating liquid from the discharge space to the suction space of said chamber, said valve extending into the discharge space for a sufficient distance to cause gas in the recirculating liquid to move beyond the path of recirculation.

4. In a self-priming centrifugal pump, a casing, an impeller rotatable within said casing, a chamber mounted adjacent said casing and divided into a suction space connected with the inlet of said impeller and separated from a discharge space receiving the discharge from said casing, a valve housing mounted in the discharge space of said chamber and having a port connecting the suction and discharge spaces in said chamber, said port being adjacent to and in line with the inlet of said impeller, and a hollow valve element mounted for sliding movement in said valve housing for conducting therethrough the entire discharge from said casing into the discharge space of said chamber and controlling the recirculation of liquid between the spaces through said port.

5. In a self-priming centrifugal pump, a casing, an impeller rotatable within said casing, a chamber mounted adjacent said casing and divided into a suction space connected with the inlet of said impeller and separated from a discharge space receiving the discharge from said casing, a valve housing mounted in the discharge space of said chamber, said housing having a plurality of internal flanges and a port between the flanges connecting the suction and discharge spaces in said chamber, and a valve mounted in said housing for conducting the entire discharge from said casing into the discharge space of said chamber, said valve having flanges seating on the flanges of said housing to control recirculation of liquid between the spaces through the port.

6. In a self-priming centrifugal pump, a casing, an impeller rotatable within said casing, a chamber mounted adjacent said casing and divided into a suction space connected with the inlet of said impeller and separated from a discharge space receiving the discharge from said casing, a valve housing mounted in the discharge space of said chamber and having a port connecting the suction and discharge spaces in said chamber, and a valve mounted in said valve housing for conducting the entire discharge from said casing into the discharge space of said chamber and controlling the recirculation of liquid between the spaces through the port, said housing and said valve having a plurality of interengaging flanges with the upper of said valve flanges having an area greater than the area of the discharge passage through said valve to cause closing of said valve responsive to the velocity of the discharge therethrough.

7. In a self-priming centrifugal pump, a casing, an impeller rotatable within said casing, a chamber mounted on said casing and divided into a suction space connected with the inlet of said impeller and separated from a discharge space receiving the discharge from said casing, a valve housing mounted in the bottom of the discharge space of said chamber and having a port connecting the suction and discharge spaces in said chamber, and a valve mounted in said valve housing for conducting the entire discharge from said casing into the discharge space of said

chamber and controlling the recirculation of liquid between the spaces through the port, said housing having a plurality of flanges with the upper one of the flanges having extensions therefrom fitting closely about said valve and said valve having a plurality of flanges with the lower one of the flanges fitting closely into said housing to guide movement of said valve.

8. In a self-priming centrifugal pump, a casing, an impeller rotatable within said casing, a chamber mounted on said casing and divided into a suction space connected with the inlet of said impeller and separated from a discharge space receiving the discharge from said casing, a valve housing mounted in the bottom of the discharge space of said chamber and having a port connecting the suction and discharge spaces in said chamber, and a valve mounted in said valve housing for conducting the entire discharge from said casing into the discharge space of said chamber and controlling the recirculation of liquid between the spaces through the port, said housing and said valve having a plurality of flanges, the movement of said valve being limited by engagement of the flanges thereof with the flanges of said valve housing.

9. In a self-priming centrifugal pump, a casing, an impeller rotatable within said casing, a chamber mounted on said casing and divided into a suction space connected with the inlet of said impeller and separated from a discharge space receiving the discharge from said casing, a valve housing mounted in the bottom of the discharge space of said chamber and having a port connecting the suction and discharge spaces in said chamber, and a valve mounted in said valve housing for conducting the entire discharge from said casing into the discharge space of said chamber and controlling the recirculation of liquid between the spaces through the port, said housing and said valve having a plurality of interengaging flanges, the lower one of said housing flanges fitting closely about said valve and the lower one of said valve flanges fitting closely in said housing to reduce leakage from the discharge space to the suction space of said chamber.

10. In a self-priming centrifugal pump, a casing, an impeller rotatable within said casing, a chamber mounted on said casing and divided into a suction space connected with the inlet of said impeller and separated from a discharge space receiving the discharge from said casing, a valve housing mounted in the bottom of the discharge space of said chamber and having a port connecting the suction and discharge spaces in said chamber, a valve mounted in said valve housing for conducting the entire discharge from said casing into the discharge space of said chamber and controlling the recirculation of liquid between the spaces through the port, said housing and said valve having a plurality of interengaging flanges with the upper of said valve flanges having an area greater than the area of the discharge passage through said valve to cause closing of said valve responsive to the velocity of the discharge therethrough, and a spring joining said housing and said valve to allow closing of said valve only at a predetermined velocity.

11. In a self-priming centrifugal pump, a casing, an impeller rotatable within said casing, a suction and a discharge conduit associated with said casing, a hollow valve element defining a passage through which the entire discharge from 75 said casing is conducted to said discharge con-

duit under all conditions of pump operation, said valve controlling a port connecting said suction conduit with said discharge conduit, and means for regulating movement of said valve responsive to the velocity of flow through said valve.

12. In a self-priming centrifugal pump, a casing, an impeller rotatable within said casing, a suction and a discharge conduit associated with said casing, a valve housing mounted in said discharge conduit, said housing having a plurality of internal flanges forming a valve chamber, a port connecting said valve chamber with said suction conduit, said port being of less cross-sectional area than said valve chamber, and a valve mounted in said housing for conducting discharge from said casing to said discharge conduit and controlling said port.

13. In a self-priming centrifugal pump, a casing, an impeller rotatable within said casing, a suction and a discharge conduit associated with said casing, valve means controlling an aperture between said discharge conduit and said suction conduit to break any siphon action in said suction conduit, and a valve for conducting the discharge from said casing to said discharge conduit, said valve controlling a port connecting said suction conduit with said discharge conduit.

14. In a self-priming centrifugal pump, a casing, an impeller rotatable within said casing, a suction and a discharge conduit associated with said casing, a valve housing mounted in said discharge conduit, said housing having a plurality of internal flanges and a port between said flanges connecting said suction and discharge conduits, and a valve mounted in said housing for conducting the entire discharge from said casing into said discharge conduit, said valve having flanges seating on the flanges of said housing to control recirculation of liquid between said conduits through said port.

15. In a self-priming centrifugal pump, a casing, an impeller rotatable within said casing, a suction and a discharge conduit associated with said casing, a port connecting said suction and discharge conduits, said port being adjacent to and in line with the inlet of said impeller, and an annular valve element having a tubular portion defining a passage through which the entire discharge from said casing is conducted to said discharge conduit under all conditions of pump operation, said valve element being exposed to pressure of fluid discharged from said pump and being actuated in response to velocity of flow through said valve element for controlling said port.

RICHARD D. CAMPBELL.
